UNITED STATES PATENT OFFICE.

EL RAY G. PALMER, OF CHICAGO, ILLINOIS, ASSIGNOR TO WALTER A. DANIELS, OF CHICAGO, ILLINOIS.

COATING-MACHINE.

1,026,765.

Specification of Letters Patent. Patented May 21, 1912.

Application filed February 5, 1912. Serial No. 675,615.

To all whom it may concern:

Be it known that I, EL RAY G. PALMER, a citizen of the United States, and resident of Chicago, county of Cook, and State of Illinois, have invented certain new and useful Improvements in Coating-Machines, of which the following is a specification, and which are illustrated in the accompanying drawings, forming a part thereof.

10 The invention relates to machines for applying a coating material to a perforated web, as the films used for the projection of moving pictures.

15 The object of the invention is to provide such a machine having improved means for preventing the accumulation of the coating material in the apertures of the web.

20 The invention contemplates means for spreading a film of the coating material upon the surface of the web and means for puncturing that part of such film which covers the perforations of the web.

25 In the accompanying drawings—Figure 1 is a side elevation illustrating a machine embodying the features of improvement provided by the invention; Fig. 2 is a plan view of the same; and Fig. 3 is a perspective view illustrating a detail of the machine.

30 The parts of the machine are preferably organized upon a stationary frame which is generally designated by the numeral 10. This frame is shown as comprising a pair of parallel side plates 11 and 12 and a plurality of connecting members, as 13, extending between the plates. A detail of the web adapted to be coated by the machine is shown at 14 in Fig. 3 of the drawings. As is usual in films used for the projection of 35 moving pictures, this web is provided with a series or row of sprocket apertures 15 extending along each of its margins. The path of movement of the web, as 14, through the machine is indicated by the broken lines 40 16—16 in Fig. 1. In practice, the web, as 14, will be drawn through the machine, whereby it will be progressively coated upon one side, from end to end, by pulling upon the end of the web.

45 50 A liquid-applying roller engageable with one side of the web 14, is shown at 17. This roller extends between and is journaled at its opposite ends in the side plates 11 and 12 and dips into a container 18. In order

that the roller 17 may be driven by the movement of the web 14, it is connected by gears 18, 19 with a guide roller 20 having sprocket teeth 21 which enter the perforations 15 of the web. As shown, the roller 17 has a continuous smooth periphery whereby coating material is applied over the entire surface of the web 14. Usually the coating material will be of such consistency that when applied to the surface of the web 14 by the roller 17, it will bridge over the perforations 15. In order that the perforations of the web will not be permanently closed in this way provision is made for puncturing the film of coating material in line with each of the perforations 15, while it is still in a fluid state. The contraction of the coating material in drying will then serve to completely clear the web perforations of such material.

As shown, provision is made for introducing a pointed needle into each of the perforations 15 of the web immediately after the application of the coating material to the surface of the web by the liquid applying roller 17. To this end, a plurality of 55 pointed needles 22 are provided. Preferably these needles are arranged in two rows or series, as 23, 24, about a spindle 25 which is rotatably mounted in the frame 10. To provide a support for the needles about the spindle 25 they are shown as being peripherally mounted upon a pair of disks 26, 27 which are carried by the spindle. In order that the needles 22 upon each of the disks 26, 27 may progressively enter the 60 perforations 15 extending along one of the margins of the web 14, provision is made for turning the spindle 25 at such a rate that the needles will move uniformly with the web. As shown, a gear 28 is mounted on the spindle 25 adjacent one end. This gear is caused to turn uniformly with the gear 18 through the use of an intermediate gear 29 which meshes with the gear 28 and with the gear 18.

Guide rollers, as 30 and 31 engageable with the back of the web 14, are preferably employed for positioning the web in front of the spindle 25 whereby its perforations will be entered by the needles 22. As shown, these guide rollers extend between the side plates 11 and 12 of the frame 10 and are journaled at their opposite ends upon such

plates. To insure that none of the coating material which has been applied to the face of the web will be collected upon the periphery of either of the guide rollers 30 and 31, each of these guide rollers is preferably provided with a pair of circumferential grooves 32, 33. These grooves are suitably spaced apart to register with the two rows of perforations 15 with which the web 14 is shown to be provided.

In some instances it may be desirable to adjust the spindle 25 in a direction parallel to the direction of movement of the web 14. For this purpose the spindle 25 is preferably journaled at its opposite ends in bearing blocks, as 34, each of which is movably mounted in a slideway 35 formed in one of the side plates, as 12, of the frame 10. Adjusting screws 36, 37 enter the slideway 35 through its opposite ends and embrace the corresponding bearing block 34 between them to hold it in adjusted position. To permit of the aforesaid adjustment of the spindle 25 without interfering with the meshing of the gears 18, 28 and 29, the gear 29 is mounted for adjustment upon a curved line about the gear 18. As shown, the gear 29 is mounted upon a shaft 38. This shaft is journaled at its opposite ends in bearing blocks, as 39. Each of these bearing blocks is fitted into a curved slideway 40 provided in one of the side plates, as 12, in the frame 10. Adjusting screws 41 and 42, preferably similar in construction to those used for adjusting the spindle 25, enter each of the slideways 40 through its opposite ends and embrace the corresponding bearing block 39 between them.

Provision is preferably made for cleaning the needles 22 during the rotation of the spindle 25 whereby each needle is cleaned after having been presented to the web 14. As shown, the disks 26, 27 dip into a container 43 which is supported in the frame 10 below the spindle 25. This container will preferably be filled with a solvent for the coating material which is used and a

brush, as 44, may be supported within the container for engagement with the needles.

If desired, a second application of the coating material may be made upon the surface of the web 14 after it passes beyond the guide roller 31. For this purpose a brush roller 45 will preferably be employed. As shown, this brush roller engages the surface of the web 14 as it turns over the guide roller 46. In order that none of the coating material which is applied by the brush roller 45 will enter any of the perforations 15 of the web, the width of the brush roller is preferably less than the distance between the two rows of perforations with which the web is provided.

I claim as my invention—

1. In a machine for coating an apertured web, in combination, liquid applying means and a puncturing needle movable into the web aperture.
2. In a machine for coating a moving web having a longitudinal row of apertures, in combination, a sprocket wheel, liquid applying means, a wheel having a peripheral row of puncturing needles, means for guiding the web over the sprocket wheel, by the liquid applying means and in front of the wheel having the peripheral row of puncturing needles and gear connection between the sprocket wheel and the said wheel having the peripheral row of puncturing needles.
3. In a machine for coating a moving web having a longitudinal row of apertures, in combination, a sprocket wheel, a liquid applying roll, a wheel having a peripheral row of puncturing needles, gear connection between the sprocket wheel and each of said other members, means for guiding the web over the sprocket wheel and liquid applying roll and in front of the said wheel having the peripheral row of puncturing needles.

EL RAY G. PALMER.
